UNITED STATES PATENT OFFICE.

WILLIAM R. FOX, OF GRAND RAPIDS, MICHIGAN.

SPACER-BAR MECHANISM FOR TYPE-WRITING MACHINES.

No. 872,809.

Specification of Letters Patent.

Patented Dec. 3, 1907.

Application filed February 1, 1907. Serial No. 355,329.

To all whom it may concern:

Be it known that I, WILLIAM R. FOX, a citizen of the United States, residing at Grand Rapids, in the county of Kent, State 5 of Michigan, have invented certain new and useful Improvements in Spacer-Bar Mechanism for Type-Writing Machines, of which the following is a specification.

This invention relates to improvements in 10 typewriting machines, the improvement pertaining particularly to the spacer bar mechanism and adjustments of a typewriter machine.

In the manufacture of a typewriter, it is 15 necessary that the spacer bar be adjustable within certain ranges to accommodate the movement of the key levers, and it is also necessary that the striking part or stop of each key lever, or other actuating part, be 20 adjustable so that the various parts can be adjusted in their relation to the spacer bar after the machine is assembled.

The objects of my invention are, first, to 25 provide a special construction of adjusting means on the key lever and an adjustable spacer bar, the same being adapted to complete adjustment without substantially varying the position of the adjustable stop or spacer bar longitudinally of the key lever. 30 Second, to provide an efficient and practical and simple means of adjusting the stop of each key lever, which contacts with and actuates the spacer bar. Third, to provide an improved sheet metal spacer bar with improved means of locking and retaining the 35 connections in position.

Further objects, and objects pertaining to 40 details of construction, will definitely appear from the detailed description to follow.

I accomplish the objects of my invention 45 by the devices and means described in the following specification.

The invention is clearly defined and pointed out in the claims.

So much of a typewriter as is necessary to 50 illustrate my improvements is clearly illustrated in the accompanying drawings, forming a part of this specification, in which,

Figure 1 is a detail view of the rear portion 55 of one side of a typewriter, partially in section, showing the rear portion of the key lever with my improved device in position; the upper portion of guide 7 and a part of spring 22 being indicated by dotted lines; Fig. 2 is

an enlarged detail sectional view on line 2—2 55 of Figs. 1 and 4, through a pair of keys at the side of the machine and through my improved spacer bar mechanism; Fig. 2 $\frac{1}{2}$ illustrates the opposite symmetrical end of the universal spacer bar and adjacent parts appearing in Fig. 2 on a reduced scale; Fig. 3 is a similarly enlarged detail sectional view taken on a line 3—3 of Fig. 2, showing the details of the adjustable stop, the key lever not being sectioned; Fig. 4 is a similarly enlarged detail inverted plan view of one end of the spacer bar; Fig. 5 is an enlarged detail view of the guide for the spacer bar attached to the spacer lever 6, taken from the right hand of Fig. 2 and the rear of Fig. 1; and Fig. 6 is a detail inverted plan view of the threaded nut 15 by which the spacer bar is adjusted on its connections.

In the drawing, all of the sectional views are taken looking in the direction of the little arrows at the ends of the section lines, and similar numerals of reference refer to similar parts throughout the several views.

Referring to the numbered parts of the drawing, the frame 1 of the machine is of the usual form, a fragment only of which is here illustrated. Across the back of the frame is the fulcrum bar 2 which carries the pivotal connection for the rear ends of the key lever 3 and spacer lever 6. The key lever 3 and spacer lever 6 are held normally upward by a spring 5, the lower end of which presses against the transverse bar 4. To the spacer lever 6 is secured a guide 7 which is slotted and receives the universal spacer bar 8, which is made of sheet metal and is turned down to form a channel, as is clearly illustrated in the cross-section in Fig. 1.

On the upper surface is cemented a cushion 9, of leather, felt, rubber, or any other 95 suitable material. The spacer bar is adjustable on its rods 17, one of which is located at each end (one only being illustrated here, as they are duplicates), by a round nut 15, which is notched on opposite sides at 16.

In the channel of the universal spacer bar is a spring slide 10, the end of which is slotted, and an upward projection 13 is formed by a kink therein. This slide is slotted at 12, and is retained within the channel by the headed rivet 14, along which it can be adjusted. The inner end is downturned at 11, forming a thumb-piece or handle by which

the slide can be moved back and forth. The outer end is deflected downward below the projecting portions a sufficient distance to form an inclined plane, so that, when the 5 slide is moved outwardly—owing to its elasticity—it will yield and slide below the nut 15, and the projection 13, referred to, will engage in the notch 16, and prevent rotation of the nut. This enables the nut to be fitted 10 so that it will turn freely. To adjust the height of the universal spacer bar, it is only necessary to withdraw the slide 10, turn the nut to the desired position by the point of a pencil—or any other pointed instrument— 15 and then move the slide back, when the elasticity of the spring on the projections will retain the nut against rotation and retain the bar snugly against the nut, at the same time preventing its accidental displacement when 20 in use.

The bar, as has been before remarked, is retained and fixed in longitudinal position to the spacer lever by the guide 7, which embraces the same. The end 8' of the bar 8 is 25 turned up into a flat blade in proximity to the guide 7, it insuring a more perfect guiding effect and preventing endwise movement of the spacer bar.

The structure of the adjustable stops on 30 the key levers 3 will now be fully explained, and the method of their adjustment, whereby the stops are retained in proper relation to the spacer bar, will be explained.

The stop 18 is formed by folding a piece of 35 sheet metal into substantially a U-shape, so that it embraces the key lever 3. Slots 21 are cut or formed in opposite sides of this stop and embrace a pin 20, which projects on one side and retains the stop from longitudinal movement, but allows the same to be 40 adjusted up and down. A hole 26 is formed just within the bottom fold of the sheet metal, as clearly appears in Figs. 1 and 3. A pin 19, suitably shouldered at each end, is 45 riveted into the upper end of the stop 18 between its sides and serves to hold the sides properly spaced. A re-curved spring 22 is engaged underneath the pin 19 at its upper end, which is suitably conformed thereto, 50 and its lower re-curved end rests on top of the key lever 3, constantly throwing the stop upwardly, which tends to raise it against the under side of the key lever 3.

Upwardly projecting lugs 24, 25, are 55 formed from the sheet metal at each end of the groove formed by the upturned sides of the stop.

A wedge 23, toothed on its lower inclined side, is inserted between the stop and the 60 lower side of the key 3, the teeth thereof projecting downwardly opposite the aperture 26 and being sufficiently spaced to receive the upwardly-projecting lugs 24, 25, before described.

65 To adjust this improved key stop, it is

only necessary to move the wedge 23 back and forth on the under side of the key lever 3. If the wedge were an inclined plane, there would be a more or less likelihood of its becoming displaced and, on the other hand, 70 it might become necessary to exert considerable force upon it. By inserting most any kind of a pointed instrument—as the end of a file shank—into the hole 26, and giving it a rotation, it will take hold of the teeth on the wedge 23 and the same can be adjusted back and forth with great ease and certainty, the action of the rotating part being to depress the stop and, as that is retained substantially against longitudinal movement, the 75 wedge can be advanced or withdrawn at pleasure by the turning of the file shank, or other instrument, back and forth. Thus a very close and accurate adjustment of the stop on the key lever is secured in an exactly 80 vertical position above the universal spacer bar, which is retained in the desired position underneath the key lever by the guide 7 heretofore referred to and described. It will thus be seen that the general adjustment of 85 the universal spacer bar can be readily secured by turning the nut 15 so as to adjust the height of the same on its supports 17, which connect the same to the escapement mechanism of a typewriter. When this general adjustment is secured, the stop on each 90 key lever is independently adjusted to accommodate the slight variations in the dip of the different keys to secure the proper release of the escapement and feed of the carriage for each key of the typewriter. 95

Having thus described my invention, what I claim as new and desire to secure by Letters Patent is:

1. In a typewriter, the combination with 105 the frame of the typewriter of the spacer lever 6; a guide 7 thereon; a universal spacer bar retained within the guide; a rod connecting said bar to the escapement and suitable adjusting means therefor; key levers to the 110 typewriter; an adjustable stop on each key lever, made of a fold of sheet metal and having vertical slots; a pin on the key lever engaging the said slots; a spring for holding said stops upward; and an adjustable wedge with 115 rack teeth, between the underside of the key lever and the adjustable stop for regulating the height of the stop vertically at a substantially fixed point on the key lever, all co-acting substantially as described and for the 120 purpose specified.

2. In a typewriter, the combination with 125 the spacer lever of a guide 7 thereon; a universal space bar formed of a channel of sheet metal; escapement connecting rod 17 screw-threaded at its lower end; the notched screw nut thereon; and a lock for the nut consisting of the spring slide 10 arranged within the channel with its end slotted and curved to pass readily outside the nut, the ends being 130

formed with projections to engage the notches in the nut, co-acting substantially as described and for the purpose specified.

3. In a typewriter, the combination with 5 the spacer lever of a guide 7 thereon; a universal spacer bar formed of a channel of sheet metal; the escapement connecting rod 17 screw-threaded at its lower end; a screw nut thereon; and a lock for the nut, consisting 10 of the spring slide 10 arranged within the channel with its end curved to pass readily outside the nut, co-acting substantially as described and for the purpose specified.

4. In a typewriter, the combination with 15 the spacer lever of a universal spacer bar formed of a channel of sheet metal; the escapement connecting rod 17 screw-threaded at its lower end; the notched screw nut thereon; and a lock for the nut, consisting of the 20 spring slide 10 with its end slotted and curved to pass readily outside the nut, the ends being formed with projections to engage the notches in the nut, co-acting substantially as described and for the purpose 25 specified.

5. In a typewriter, the combination with the spacer lever of a universal spacer bar formed of a channel of sheet metal; the escapement connecting rod 17 screw-threaded 30 at its lower end; the screw nut thereon; and a lock for the nut, consisting of the spring slide 10 with its end curved to pass readily outside the nut, co-acting substantially as described and for the purpose specified.

35 6. In a typewriter, the combination with the key levers of a universal spacer bar formed of a channel of sheet metal, the edges thereof being turned downward; and connecting devices within the channel for securing 40 the same to the connecting rod, for the purpose specified.

7. In a typewriter, the combination of the key lever 3; a universal spacer bar stop 18 formed of sheet metal folded to embrace the 45 key lever 3 and having a slot 21 formed therein; a pin 20 on the lever engaging the said slot; a shouldered rivet 19 between the uppersides of said stops; a spring 22 for throwing the stop normally upward; lugs 24, 25, at 50 the ends of the channel formed by a fold of sheet metal; and an adjustable wedge 23 with rack teeth, arranged between the lower side of the key lever 3 and the bottom part of the stop, the teeth being arranged to engage the lugs 24, 25, a round hole being formed through the lower part of the stop to permit the insertion of an instrument for adjusting the wedge, co-acting for the purpose specified.

60 8. In a typewriter, the combination of the key lever 3; a universal spacer bar stop 18 formed of sheet metal folded to embrace the key lever 3; a shouldered rivet 19 between the uppersides of said stops; a spring 22 for throwing 65 the stop normally upward; lugs 24, 25, at

the ends of the channel formed by a fold of sheet metal; and an adjustable wedge 23 with rack teeth, arranged between the lower sides of the key lever 3 and the bottom part of the stop, the teeth being arranged to engage the lugs 24, 25, a round hole being formed through the lower part of the stop to permit the insertion of an instrument for adjusting the wedge, co-acting for the purpose 70

75 9. In a typewriter, the combination of the key lever 3; a universal spacer bar 18 formed of sheet metal folded to embrace the key lever 3; a shouldered rivet 19 between the upper sides of said stops; a spring 22 for throwing 80 the stop normally upward; lugs 24, 25, at the ends of the channel formed by a fold of sheet metal; and an adjustable wedge 23 with rack teeth, arranged between the lower side of the key lever 3 and the bottom part 85 of the stop, the teeth being arranged to engage the lugs 24, 25, a round hole being formed through the lower part of the stop to permit the insertion of an instrument for adjusting the wedge, co-acting for the purpose 90 specified.

10. In a typewriter, the combination of the key lever 3; a universal spacer bar stop 18 formed of sheet metal folded to embrace the key lever; a spring 22 for throwing the stop 95 normally upward; and an adjustable wedge 23 with rack teeth, arranged between the lower sides of the key lever 3, and the bottom part of the stop, a round hole being formed through the lower part of the stop to permit the insertion of an instrument for adjusting the wedge, co-acting for the purpose 100 specified.

11. In a typewriter, the combination with the key lever of a universal spacer bar stop embracing the same; a spring for holding said 105 stop normally upward; an adjustable wedge between the key lever and the stop for adjusting the elevation of the stop vertically on the key lever; and a transverse guide for the said stop, for the purpose specified. 110

12. In a typewriter, the combination with the key lever of a universal spacer bar stop embracing the same; a spring for holding said stop normally upward; and an adjustable wedge between the key lever and the stop 115 for adjusting the elevation of the stop vertically on the key lever, for the purpose specified.

13. The combination with the type key levers, of a universal spacer bar having upturned ends of sheet metal in planes transverse to the said bar; spacer levers 6 towards each end of the said universal bar; guides 7, secured to the said spacer levers, embracing the said universal bar and within the upturned ends, whereby the longitudinal movement of the bar is obviated, as specified. 120

14. The combination with the type key levers of a universal spacer bar with an upwardly-projecting guide portion at each end 130

to restrict the longitudinal movement of said bar; spacer levers at each side of the said type key levers in proximity to the upturned guide portions and between the same and 5 the type key levers, whereby the universal bar is guided in its vertical movement and a rubbing contact of its connections with the key levers avoided.

In witness whereof, I have hereunto set my hand and seal in the presence of two wit- 10 nesses.
